UNITED STATES PATENT OFFICE.

TIMOTHY F. MANNIX, OF FLORAL PARK, NEW YORK.

APPARATUS FOR WASHING AUTOMOBILES.

Application filed January 31, 1922. Serial No. 533,017.

To all whom it may concern:

Be it known that I, TIMOTHY F. MANNIX, a citizen of the United States, and resident of Floral Park, in the county of Nassau and 5 State of New York, have invented certain new and useful Improvements in Apparatus for Washing Automobiles, of which the following is a specification.

In the washing of automobiles in large 10 garages certain parts of the operation are customarily performed by the use of a bucket containing soap and water, and into which a sponge may be dipped. Trouble, delay and unsatisfactory work often results 15 from the use of an ordinary pail or bucket for this purpose. The main object of my invention is to provide a special construction by means of which time may be saved, trouble avoided, and more satisfactory re- 20 sults accomplished, and which at the same time is easy to manufacture and keep in proper working condition.

In the accompanying drawing I have illustrated one embodiment of my invention, although it will of course be evident that changes may be made in details of construction without departing from the scope of 25 my invention. In these drawings:—

Fig. 1 is a perspective view, a portion of 30 the wall of the bucket being broken away.

Fig. 2 is a central vertical section,

Fig. 3 is a section showing the parts in partially inverted position, and

Figs. 4 and 5 are sectional details.

35 My improved apparatus includes, or is attached to, an ordinary metal bucket or pail having a slightly tapered wall 10, a beaded upper edge 11, and a bale 12 secured to ears 13, or in any other suitable manner. So far 40 as concerns the main features of my invention this pail may be of any ordinary type of construction, such as is now used on the market, except that the upper edge shall be designed or adapted for the attachment of 45 the screen supports. As shown there is provided an annular reinforcing wire 14 around which the metal of the wall 10 is folded, and lying outside of the plane of the wall so as to present a ridge, flange or bead on the 50 outer surface at the upper edge, as shown particularly in Fig. 4.

Within the bucket there is provided a circular reticulated or foraminous diaphragm or partition 15 preferably in the form of a 55 wire mesh screen. I do not wish to be limited to any particular size of mesh, but it

should be sufficiently coarse to permit the free passage downwardly therethrough of any particles of sand or dirt which are introduced into the pail or the water above the 60 screen, and to prevent the sponge from passing downwardly therethrough or the soap upwardly therethrough. It should also be of such mesh as will not materially interfere with a free circulation of the water in the 65 pail as a sponge is introduced and withdrawn. The wires forming the mesh should be of sufficient stiffness to give the screen substantial rigidity. The wires may be spaced about one-half of an inch apart. 70 The screen includes a peripheral reinforcing or frame member 16 in the form of a comparatively stiff wire bent to circular form, and the peripheral edge of the screen is bent around this frame member, as shown partic- 75 ularly in Fig. 5, or is soldered thereto or permanently attached in any suitable manner. The diameter of the screen is of approximately the internal diameter of the pail at a point a very few inches above the 80 bottom of the pail. It is not intended that the screen shall make a close friction fit at this point, as slight lateral movement is not materially objectionable. It should be of such size that it may be lowered to the 85 proper position without danger of binding in spite of slight inaccuracies or crudity in manufacture or assembly.

The screen is supported by three sup- 90 porting rods 17 adapted to lie closely ad- jacent to the inner surface of the wall 10 and extending upwardly along said surface from the periphery of the screen to the upper edge of the pail. These supports are preferably in the form of comparatively 95 stiff wires or rods with their lower ends curved inwardly to form loops or eyelets 18 receiving the peripheral or frame member of the screen. Their upper ends are bent outwardly to engage the upper edge of the 100 pail. Thus the frame members 17 have no projecting parts intermediate of their ends, and lie parallel to and closely adjacent the wall, so that they obstruct to the minimum extent the space in the pail above the 105 screen. I preferably permanently attach the screen to the pail, by forming one of the members 17 at its upper end with an eyelet 19 completely encircling the beaded edge of the pail, and extending through a small 110 aperture therein, as shown particularly in Fig. 4. One or more of the other supports

are provided with hook shaped end portions 20 which may be snapped over the upper edge and frictionally retained in place. These hooks may be lifted off the edge by applying sufficient pressure, and the screen may then be lifted out of the bucket, although remaining attached by one of the supports through the medium of the eyelet 19, if desired. This permits the pail 10 to be freely washed out and clean soap inserted beneath the screen. The frictional engagement of the hooked portions 20 is such that the pail may be inverted, as shown in Fig. 3, without liability of the screen 15 being displaced. Furthermore, when inverted the screen holds the soap in place.

By means of my improved construction it will be noted that if the pail be accidentally tipped over the soap will not be 20 spilled out or the screen displaced. If a dirt covered sponge be dropped into the water the dirt may fall through the screen. It is immaterial that some of this lands on the soap, as the soap and sponge are 25 always separated by the screen, and the dirt cannot be wiped off the soap or off the bottom of the pail by the sponge when the screen is in place. Upon inverting the pail the dirt may flow out with the water, while 30 the soap remains, and the pail may be rinsed out by inducing fresh water, agitating, and again dumping while the soap still keeps its position. The presence of the screen and its supports in the bucket does not prevent 35 the bucket from being used for ordinary purposes, such for instance as filling the automobile radiator, assuming of course that the sponge and soap be removed.

I have previously referred to the use of 40 my improved device for the washing of automobiles. It will of course be evident that

the device may be used for washing any other object or article, and that a wash rag or brush may be employed instead of a sponge, and depending upon the character 45 of the article to be washed and the dirt or other foreign matter to be removed. The soap employed may of course vary with the character of the article being washed, and in some cases may be entirely omitted, as 50 it forms no portion of the construction. The device has material advantages, even though no soap is employed, as it keeps the sponge from coming in contact with the dirt on the bottom of the pail, and the screen cannot 55 be displaced if the pail be tipped over. It can be easily removed when desired.

Having thus described my invention, what I claim as new and desire to secure by Letters Patent is:—

In combination, a pail having a beaded edge around the open top thereof, a circular wire screen of a diameter approximately equal to that of the interior of the pail at a point spaced a short distance above the 60 bottom and adapted to support a sponge and retain soap therebeneath, and a plurality of supporting members hinged to the peripheral portion of the screen and extending upwardly along the inner surface of the 65 wall of the pail, the upper end of at least one of said members encircling and permanently secured to said beaded edge and the upper end of one or more of the other of said members receiving and being detachably secured 70 to said beaded edge, whereby said screen is secured to the pail and upon inverting the pail, is removably retained in position.

Signed at New York in the county of New York and State of New York this 30th 80 day of January A. D. 1922.

TIMOTHY F. MANNIX.
